THERMIONIC AMPLIFYING DEVICE

Application filed May 2, 1929. Serial No. 359,813.

My invention relates in general to devices for amplifying energies, and in particular to a device for use in connection with radio translating devices.

5 It is well known to those skilled in the art that in the ordinary three-electrode thermionic device, such as the ordinary vacuum tube as used in a radio receiver, when the control or signal grid is negatively charged, there is 10 a very marked repelling action to the electronic stream due to this negative charge impressed on the grid by the negative half of the applied E. M. F. When the grid of such a tube is negatively charged, many of the 15 electrons are forced back to the cloud of electrons already surrounding the cathode of the tube, some of the electrons being actually forced back into the cathode surface, which congestion is ordinarily referred to as filament congestion. In such a vacuum tube 20 there is also capacity existing between the electrodes due to electrostatic lines of force.

In an attempt to overcome some of the disadvantages above enumerated in connection with the three-electrode vacuum tube, radio engineers have designed a four-electrode vacuum tube, sometimes referred to as a plate-screen, or screen grid type tube. This tube substantially eliminates the capacity existing between the anode and the control grid, but the plate impedance of this tube is exceedingly high, and it is only at considerable cost and complication of construction that the maximum amplification of which this 25 tube is capable is possible. It is, furthermore, well known that attempts have been made to change the function of the electrodes of this four-electrode vacuum tube and use 30 the plate-screens as a signal grid, while applying a positive potential to that electrode which was originally designed to be used as a signal grid. In such a make-shift use of this tube, exceedingly high capacity exists 35 between the signal grid and the anode, and the amplification of which the tube is capable is thus materially reduced.

In creating my invention, I have sought to provide a thermionic device which shall have 40 all the advantages of the vacuum tubes above

mentioned, but shall overcome the disadvantages thereof.

It has, therefore, been an object to produce a device in which the filament congestion and space charge shall be relieved, and in 55 which the density and uniformity of the electronic stream shall be increased.

Other objects are to increase the mutual conductance; to increase the amplification constant; and to reduce the plate impedance. 60

Moreover, in my device, the inter-electrode capacity is greatly reduced.

Furthermore, because my invention reduces the plate impedance, it is possible through simpler and more economical structures to get maximum amplification. 65

In my device, in addition to the customary cathode, anode, signal grid, and plate screens, I also use an additional electrode which is preferably in the form of a grid located between the filament and control grid in direct current types, and between the cathode and control grid in the alternating current types. To this fifth electrode is applied a definite and constant potential or influence. Because 70 of the potential applied and geometric location of this fifth electrode in the tube with respect to the electron emitting electrode, it has a great power of attraction for the electrons. In fact, the action of this electrode could almost be described as having a sucking effect upon the electrons from the filament or cathode, and, therefore, the negative cloud of electrons surrounding the filament or cathode is broken up. The action relieves 75 filament congestion and hence clears the path for a free and dense electronic stream between the electron emitter and the anode. Since as is well known, the sensitivity of the control of the signal grid is definitely limited by the negative cloud of electrons surrounding the electron emitter, my device has a wider control range of the signal grid, and, therefore, greater amplifying ability because of the 80 fact that the electronic congestion is relieved. 85

The above objects and advantages have been accomplished by the device shown in the accompanying drawings, of which:

Fig. 1 is an exterior view of my complete device. 100

Fig. 2 is an enlarged fragmentary, vertical, sectional elevation thereof, showing the various parts of the device in somewhat of a diagrammatic manner.

5 Fig. 3 is a sectional plan view of my device, and is taken on line 3—3 of Fig. 2.

Figs. 4, 5, and 6 are diagrammatic views showing typical circuit arrangements for employing my device in a system for the 10 amplification of electromagnetic impulses.

Referring to Figs. 1 to 3, inclusive, it will be seen that my device is made up in the form of the standard vacuum tube, and comprises a base 10 carrying the usual evacuated envelope 11, within which the electrodes of my device are disposed. As is customary the envelope is formed with the glass stem 12 which carries the supporting and anchoring wires for the various electrodes.

15 The stem 12 carries two upwardly extending supporting wires 13 to the upper portions of which is secured the anode 14 of my device. This anode is preferably in the form of a cylindrically shaped plate and is secured by any suitable means to the supports 13. This anode 14 is surrounded by an outer anode screen 15 which is arranged in interspaced relation therewith. This screen is preferably made in the form of a helix, the turns 20 of which are supported at diametrically opposite sides by means of wire supports 16. The lower ends of these wire supports are fastened together by means of a horizontally arranged circular brace 17. Arranged over the upper end of the outer anode screen 15 is a shielding plate 18 for the anode which is preferably of substantially the same size as the diameter of the outer anode shield, and which is securely fastened to the upper 25 ends of the wire supports 16. This plate is provided in its center with an aperture 19 for the passage of other of the electrodes of the device, to be hereinafter described. The extreme upper ends of the wire supports 16 are attached to horizontal supporting wires 20 which are carried by the glass brace or bridge 21 to be hereinafter described. Arranged within and in interspaced relation with the anode 14 is an inner anode screen 25.

30 This anode screen is also made of wire and may be helical in form. This inner screen is provided at diametrically opposite sides with supporting wires 26. The lower ends of these supporting wires are carried by the stem 12 and they extend upwardly and have their upper ends securely fastened to the shielding plate 18. The inner and outer anode screens 25 and 15, respectively, are, therefore, mechanically and electrically tied 35 together at their upper ends. The lower ends are connected together by means of a lead 27 which connects the horizontal circular brace 17 with one of the supporting wires 26.

Arranged within the inner anode screen 25 is the signal grid 30. This grid is pref-

erably cylindrical in form and has a supporting wire 31 arranged at one side thereof. The upper end of this supporting wire extends through the opening 19 in the shielding plate 18 and is supported by means of the horizontal supporting wire 32 carried by the glass bridge 21. The lower end of the supporting wire 31 is carried by an insulating bead 33 preferably of glass. Arranged concentrically within the grid 30 is the cathode screen 34 of my device. This electrode may be in the form of a helix, which is carried by a supporting wire 35 extending through the electrode and at one side thereof. The lower end of this wire is supported by the glass stem 12 of the device while the upper end thereof is attached to the horizontal supporting wire 36 of the glass bridge 21. A supporting wire 29 is attached near the lower end of the supporting wire 35, and its upper end is mounted in the insulator 33, whereby the insulator and the signal grid is supported. Arranged concentrically through the cathode screen 34 is the cathode or filament 37 of my device. This electrode is preferably in the form of a single wire, in direct current types, and is supported at its lower end by a conductor 38, carried by the stem 12, and at its upper end by a conductor 39. The conductor 39 extends horizontally from the upper end of the filament 37 and is provided with a vertical portion 40 which passes through the bridge 21 and extends downwardly to a point substantially opposite the stem 12. A horizontally arranged conductor 41 has its outer end attached to the vertical conductor 40, and its inner end 42 bent downwardly and secured in the stem 12. Carried by the top of the envelope 11 is a signal grid cap 45 which is connected preferably to the supporting wire 31 of the signal grid 30 by means of a lead 46. The lower end of the conductor 40 is preferably provided with an inwardly bent portion 47 at the inner end of which is a metal foot 48 which carries the customary getter 49.

Carried by the base are the prongs of my device, comprising a negative filament prong 50, a positive filament prong 51, a cathode screen prong 52, an anode prong 53, and an inner and outer anode shield prong 54. The negative filament prong 50 is connected to the conductor 38 by means of a lead 55, while the positive filament prong 51 is connected to the end 42 of the horizontal conductor 41 by means of a lead 56. The cathode screen prong 52 is connected by means of a lead 57 to the conductor 35. The anode prong 53 is connected to one of the supporting wires 13 of the anode by means of a lead 58. The inner and outer anode screen prong 54 is connected with one of the supporting wires 26 by means of a lead 59.

Referring now to the diagrams, Fig. 4

represents a transformer-coupled, radio receiving circuit; Fig. 5 shows a tuned-impedance circuit; and Fig. 6 shows an auto-transformer circuit. In each of these circuits 5 60 represents the antenna; 61 represents the primary winding of the antenna inductance 62; and 63 represents the secondary winding of the antenna inductance. A variable condenser 64 is shunted across the secondary 10 winding 63 of the antenna inductance for the purpose of tuning this circuit.

Referring now more specifically to the transformer-coupled circuit of Fig. 4, it will be seen that the signal or control grid 30 is 15 connected by means of a lead 65 to one side of the secondary winding 63 of the antenna inductance, while the other side of this winding is connected, in cases where a grid bias battery 93 is used, by means of a lead 98 to 20 the negative side of the battery. The positive side of the battery 93 will be connected by means of a lead 66 to the negative side of the high potential battery 67. The positive side of the high potential battery 67 is connected by means of a lead 68 to one side of the primary 69 of the radio frequency transformer 70. The other side of this winding is connected to the anode or plate 14 of my 25 device by means of a lead 71. Of course, when the grid bias battery 93 is not used, the leads 98 and 66 are connected together, or the battery is replaced by a resistance. A 30 variable condenser 72 may be used, and when used, is shunted across the primary winding 69, whereby this winding is tuned. The filament 37 in direct current types is connected to a battery 73 of low potential through a 35 rheostat 74 for controlling the heat of the filament. In this and the other types of circuits shown in Figs. 5 and 6, it is obvious that the battery 73 and the rheostat 74 will be 40 omitted when the device is to be used on alternating currents. It will be clear that 75 is the secondary winding of the radio frequency transformer 70, and this is connected 45 to the output terminals 76 and 77. A variable condenser 78 is provided for tuning the secondary winding 75. The inner and outer anode screens 25 and 15, respectively, are 50 connected by means of a lead 79 to the high potential battery 67 in such a manner that the potential received by the screens may be varied. A lead 80 connects the lead 66 extending to the negative side of the high potential battery 67 with one side of the filament 37, and a fixed condenser 81 is connected 55 across leads 79 and 80 for furnishing a path for high frequency current from the anode screens 25 and 15 to the filament 37. The 60 cathode screen 34 is connected to the lead 66 through a battery 82 by means of a lead 83, whereby this screen is supplied with a positive potential. A fixed condenser 84 is 65 connected between the filament 37 and the lead

83 for the passage of high frequency currents.

In the impedance tuned circuit of Fig. 5, the connections to the various parts of my device are substantially the same as those above described in connection with Fig. 4 except that the positive side of the high potential battery is connected to one side of an impedance 85, the other end of this impedance being connected to a lead 86, the impedance being provided with a condenser 92 for tuning the same. One end of the lead 86 is connected to the anode 14, while the other end is connected to one of the output terminals 87 through a coupling condenser 88. The other output terminal 89 is connected to a lead 90, and a lead 91 connects the lead 90 with the negative side of the filament 37. When a grid bias battery 93 is employed in the circuits of Figs. 5 and 6, the positive side of the battery is connected to the lead 90, and the negative side to the grid return end of the secondary winding 63 of the antenna inductance 62 by means of a lead 99. A variable resistance 95 is placed between the output terminals 87 and 89. In alternating current types, as is well known, the return leads are brought back to the cathode terminal instead of the filament.

In the autotransformer arrangement shown in Fig. 6 the connections are substantially the same as in the circuit arrangement of Fig. 5, except that an autotransformer 96 is connected between the lead 90 and the output terminal 87, the coupling condenser 88 being connected to the variable tap of the autotransformer by means of a lead 100. The autotransformer is provided with a variable condenser 97 for tuning the same.

While I have shown and described my invention as applied to direct current types, this is simply for illustrative purposes, and it is obvious that my invention is applicable to alternating current types as well. Obviously, when my invention is used as an alternating current device, the grid bias battery 93 will be replaced by suitable resistance.

It is preferable in the above described circuits to provide a by-pass around the high potential battery 67 by means of a condenser 94.

If desired, a high impedance winding may be inserted in the screen grid circuit, and one may also be placed in the cathode screen circuit for the purpose of further stabilization.

For convenience in the appended claims, I have referred to the circuit which includes the anode screen as the anode screen circuit; the circuit which includes the cathode screen as the cathode screen circuit; and the circuit which includes the cathode as the cathode circuit.

While I have shown many of the electrodes of my device as being formed of wire

in helical shape, it is obvious that a wire gauze or wire mesh may be used if desired.

These and other modifications of the details herein shown and described may be made without departing from the spirit of my invention or the scope of the appended claims, and I do not, therefore, wish to be limited to the exact embodiment herein shown and described, the form shown being merely a preferred embodiment thereof.

Having thus described my invention, what I claim is:

A thermionic amplifying device, comprising an electron emitting cathode, an anode, a signal grid located between the cathode and the anode, an inner screen located between the anode and the signal grid, a cathode screen between the signal grid and the cathode, and an outer anode screen surrounding the anode.

In testimony whereof, I have hereunto signed my name.

STANLEY W. BROWN.
